UNITED STATES PATENT OFFICE.

EMIL JAGENBERG, OF DUSSELDORF, GERMANY.

LABELING-MACHINE.

1,173,578.

Specification of Letters Patent. Patented Feb. 29, 1916.

Application filed April 16, 1915. Serial No. 21,846.

To all whom it may concern:

Be it known that I, EMIL JAGENBERG, a subject of the German Emperor, and resident of 107 Himmelgeisterstrasse, Dusseldorf, Germany, manufacturer, have invented certain new and useful Improvements in Labeling-Machines, of which the following is a statement.

The present invention relates to a labeling machine which is essentially characterized by a novel arrangement for supporting the labels in the pile and by a new design of the roller for transferring the labels to the articles to be labeled. The new supporting arrangement allows of drawing particularly large labels in a reliable and very rapid manner from under the pile. The new design of the transfer roller allows of pasting particularly large labels smooth and cleanly in a reliable and rapid manner.

My invention comprises, besides those hereinbefore mentioned, also other features, which shall be more particularly described in the following description and be specified in the claims.

In the accompanying drawing the labeling machine according to the present invention is exemplified in a constructional form.

Figure 1 is a side elevation of the machine. Fig. 2 is a vertical longitudinal section through the machine on the line A—B in Fig. 1. Fig. 3 is a side elevation of the supporting arrangement. Fig. 4 shows the arrangement according to Fig. 3 in a different position. Fig. 5 is an elevation of a part of the arrangement shown in Figs. 3 and 4. Fig. 6 is a section through the rollers.

On the body 1 of the machine are fitted two standards 2, which have bracket arms 3 extending at the top to both sides. These brackets 3 are connected with each other by means of rods 4 and shafts 5 (shown broken off in Fig. 1). In the eyes 6 of these brackets 3 are fitted studs 7 which carry at the top guide rails 8 for a slide 9 sliding on them.

On the slide vertical plates 11 are secured by means of adjustable angles 10, and said plates 11 project through the slide. These plates 11 form a vertical shaft, the inside width of which can be readily varied by adjusting the angles. On either end of the two shafts 5 is fitted a cam 12 and to each one end of the said shafts 5 is fitted a lever 13 and at the other end a lever 14 respectively, which is coupled by a rod 15 hinged to it to the second lever 14. By rocking the one or

the other lever both shafts 5, and thereby also the cams 12 are revolved, so that the guides 8 bearing on them are raised and lowered. To the slide 9 are fitted two outwardly extending arms 16, to the ends of which two rods 17 are linked, which are movably coupled to two levers 18. The levers 18 are pivotally fitted to the standards 2 and are provided with revoluble rollers 19 which bear against two cam disks 21 fitted to the shaft 20 journaled in the standards 2. To the ends of the one rod 4 are fitted two arms 22 which are coupled by means of long springs 23 with the upward bent ends 24 of bars 25 provided at the far end of the slide 9. These springs 23 draw the slide to the one side, pressing the rollers 19 against the cam disks 21. At two opposite walls 11 bell cranks 27 are journaled between ears 26, and the downward pointing arms of said bell cranks have tongues 28, the other arms being linked to bars 29, which are likewise held by aid of straps 30 hinged thereto to the ears 26. In the bars 29 are fitted pins 31, at the ends of which rollers 32 are journaled. These rollers 32 bear during the reciprocating travel of slide 9 on cam-rails 33 (Figs. 2 and 5) which are secured to the slides 34 traveling in guides 35 held to the standards 2 by means of pins 36. The slides 34 carry below rollers 37 which bear against cam disks 38 fitted to shaft 20. The said cam rails 33 are coupled to arms 39 fitted to guides 35, by means of springs 40, which tend to draw the slides 34 downward. To the underside 9 are secured pillars 41, which hold below a rack 42. This rack engages in gears 43, which are secured to shafts 44 running in brackets 45 fitted to the guide rails 8. The shafts 44 have about their middle roller-like, cylindrical enlargements 46, the upper contact line of which is at the same level with the tongues 28. The walls 11 which extend beyond the shafts 44 possess small lugs 47 projecting between the enlargements 46.

On the shaft 20, which carries a driving pulley 48, is fitted a gear wheel 49, which meshes with another gear wheel 50 fitted to the shaft 51, likewise journaled in the standards 2. On the shafts 20 and 51 sectional rollers are fitted as are disclosed by the United States specification 860,148. On shaft 20 the segment 52 is held by the disks 53, and on shaft 51 the segment 54 is held by disks 55. Against the segment 52 bears an

adjustably journaled roller 56 and against the lateral a roller 58 dipping into the gum vessel 57, from which latter roller 58 the surplus gum is scraped off by an adjustable 5 ledge 59. In the disks 55 a shaft 60 is journaled to the outer end of which is fitted an arm 61 with a roller 62, which bears against a cam disk 63 fitted to shaft 51. Between the disks 55 several hooked arms 64 and 10 levers 65 are fitted to shaft 60 of which the former are pressed against the edge of the segment 54 by springs 66, which are secured to the ends of levers 65 and to a rod 67 fitted in one of the disks 55.

15 Behind the segment 54 are arranged revoluble in the disks 55 several rollers 68 at such a pitch from the shaft 51, that the points of said rollers 68 farthest from the said shaft 51 are equally far from the center 20 of shaft 51. If these rollers are of the same diameter their shafts will lie in a cylindrical plane. The segments 52 and 54 have during their rotation a clearance equal to the thickness of one of the labels to be gummed on, 25 and beneath the lower segment roller a table 70 supported on a pillar 69 is disposed at an adjustable distance equal to the height of the article to be labeled below the segment 54 when it is in its lowest position.

30 Under the table 70 a slide 71 is arranged, the guides 72 of which are supported by pillars, which are slidably fitted in sleeves 74 of the body 1 of the machine, so that the slide can be raised and lowered. The lower 35 ends of the pillars 73 are hingedly coupled by straps 75 with bell cranks 76, which are pivoted to brackets 77 on the body of the machine, and the free arms of which are coupled with each other by means of a bar 40 78 hinged thereto. To the one bell crank, furthermore, is hinged a rod 79 the end of which carries a fork 81 encompassing the shaft 80 and to which a roller 82 is fitted, which rides on a cam disk 83 on shaft 80.

45 A spring 84, which is secured to the rod 78 and to the body of the machine presses the roller permanently against the cam disk 83. The shaft 80 journaled in the body of the machine is driven from shaft 86 by means of 50 bevel gears 85, which are again driven by bevel gears 87 from the vertical shaft 88. The shaft 88 is driven from shaft 51 by bevel gears 89. To the shaft 80 is fitted an eccentric 90, which by means of rod 91 reciprocates lever 92, on the shaft 94 of which, 55 journaled in a bracket 93 on the machine body a long lever 95 is fitted, which is coupled by means of a rod 96 to the one end of the slide 71. The eccentric 90 will therefore reciprocate the slide 71. On the latter are provided several vertical abutment arms 97, which project through a long slot in the table 70. To the guides 72 are revolvably fitted two shafts 98, to which upward extending flat laths 99 and one each downward 60 65

extending arm 100 are fitted. The laths are disposed at both sides of the table, and the arms 100 ride, when the guides 72 are raised and lowered, on stationary cam rails 101, against which they are pressed by a spring 102. To the slide 71 are, furthermore, fitted on either side each two laths 104 held by a pillar 103, in which two bolts 105 are slidably fitted, which carry on studs at their upper ends rails 106 and on which 75 springs 107 are fitted, which bear above against rings 108 fitting on the pins, and thereby hold the rails 106 in raised position.

On the machine body two rods 110 are movably fitted in two guides 109, said rods 110 being rigidly connected at the top by means of a cross piece 111 and below by means of a rod 112. The rod 112 is coupled by means of a strap 113 with a bell crank 114, which is journaled on a bracket 115 and to the other arm of which a rod 116 is adjustably fitted by means of a screw bolt. This rod has at its other end a fork 117 encircling the shaft 80, and on the said fork is fitted a roller 118, which is pressed by a spring 119 secured to the rod 116 against a cam disk 120 fitted to the shaft 80. The cross piece 111 has an arm 121, which bears a guide 122 for a rod 124 weighted below with a heavy plate 123 and two plates 125, 95 to each of which are secured vertically adjustable, by means of screw bolts two bars 126. To these bars 128 are fitted, which are forced by springs 129 against the bar 124, or, in other words, against each other. 100

Next to the table 70 on the machine body 1 is secured a bracket 130 in which three slides 131, 132 and 133 are arranged above each other, of which the uppermost slide 131 is coupled by a strap 134 with a lever 135, 105 and the two other slides 132 and 133 by straps 136 and 137 respectively jointly to the lever 138. The two levers are pivoted to the machine body and are coupled below by bolts adjustably to rods 139 and 140 respectively, the other ends of which have forks 141 and 142 respectively, encircling shaft 86. On shaft 86 are fitted cam disks 143, 168 against which ride the rollers 144 and 145 respectively fitted to the forks and under action of springs 146 and 147, respectively. To the free end of slide 131 is fitted a plate 148, and the slide 132 also carries a plate 149, to which a brush 151 is secured by means of a hinge 150, which brush 151 is elastically supported in its horizontal position by a spring 152. To the lowermost slide 133 is secured a fork 153, in which a roller 154 is journaled. A similar roller 155 is stationarily journaled in a fork 125 157 supported by a pillar 156, and two rollers 158 are journaled in forks 159 which are fitted to plate 161 supported by a pillar 160. To this plate 161 are fitted ledges 162, which are at the same level with the horizontal 130 135

tangential plane to the rollers. At the same level a plate 163 is supported by arms 164 on brackets 165, in which a belt pulley 166 is journaled, around which a conveyer belt 167 runs leading to a pulley not shown in the drawing.

The machine operates in the following manner: The labels placed into the shaft formed by the plates or walls 11 there rest 10 on tongues 28, rollers 46 and the slightly inwardly curved projections 47. Thus even very large labels will be supported by this arrangement in a very reliable manner. The slide 9 with the pile of labels is operated 15 by the driven cam disks 21 and the levers 18 and thereby reciprocated. Thereby the rollers 44, 46 are revolved by the rack 42 and the gears 43 on the upper side in always the same sense and at the same velocity as the 20 slide, so that the rollers will roll on the lowermost label. The segment rollers, however, continuously revolve in one direction, the segment 52 receiving gum from the roller 56. When at the stroke to the left 25 (Fig. 2) the pile of labels moves over the segment rollers, the segment 52 will roll on the pile of labels, and the lowermost label will be retained by the gum and wrapped onto the segment. Thereby the label is 30 drawn from the pile and for assisting this the rollers 32 ride during this movement of the slide 9 on the cam rails 33 so that the bars 29 are raised, and thereby the tongues 28 are swung toward outside. The shoulders 47 extend but a little only under the edge of the label, so that they will not prevent the individual labels being drawn off, as their edges will, thereby, bend slightly over. At the return stroke of the label container (to the right in Fig. 2) the segment 35 52 is below, so that no part of the segment roller will come into contact with the pile of labels, and the cam rails 33 are now drawn downward by springs 40, as the cam disk 38 admits of this. During the return stroke of the slide 9 the tongues, thus, remain under the pile of labels. The label which has stuck to the segment 52 is transferred to the lower segment roller by the 40 grippers 64 seizing the front-edge of the label and pressing it against the segment 54. When the segment rollers continue their revolution the label is, therefore, peeled off from the segment 52 and taken up by the 45 lower segment roller so that it lies there with the gummed side outside on the segment 54 and the rollers 68. The grippers 64 are operated simultaneously and properly timed by the cam disk 63. The label is further held to the lower segment roller by a fluted roller 169, which is rockingly supported by arms 170 and is pressed by a weight 171 against the segment roller. Simultaneously with these operations also the 50 slide 71 reciprocates. During its stroke to

ward the segment rollers the guides 72 are lifted by the cam disk 83, while during its return stroke the guides 72 are lowered. During the forward stroke, therefore the dogs 97 project through the slots in the 70 table 70, whereas during the return stroke the dogs travel under the level of the table. The articles placed on the right hand end of the table (Fig. 2), which are to be labeled, will, therefore, be intermittently advanced 75 toward the segment rollers. At the raised position of the slide 71 also the ledges 99 are raised, so that they prevent the articles from slipping sidewise from the table. At the return stroke of the slide 71 the ledges 99 are rocked outward by the cam rails 101, so that the articles to be labeled may be conveniently placed on the table 70. The lower segment roller travels at its under side in the same direction in which the articles are 80 advanced. The label on the lower segment roller will therefore be applied to the article advancing under it. The grippers 64 are then lifted off by the cam disk 63 so that the label is held by the gum to the article. The slide 71 is now advanced more rapidly than the circumferential velocity of the segment rollers. Therefore the label, which has already been stuck with its front edge to the article will be carried along by the latter 85 and be drawn off from the rollers 68. The respective roller 68 which, at the moment, is in contact with the article will roll down and stroke the label smooth on the article. The present arrangement, thus, allows of 90 very rapidly labeling the articles, the label being at the same time smoothed down and stretched taut. During this operation the parts of the label extending at the sides beyond the article will be supported by the 95 ledges 106 in a horizontal position. At the end of its advance under the segment rollers the article passes beneath the stamp 123, which, when the article is at rest, is pressed against the same by the bars 110 being lowered by means of the cam disk 120, so that the freshly gummed on label is pressed on 100 tightly. At the same time the brushes 128 move downward and thereby smooth the 105 projecting parts of the label over and 110 against the sides of the article. At the next advance of the slide 71 this article is then pushed in front of the slides 131, 132, 133 and onto the rollers 154, 155, and then, when the article is at rest, the slides 132, 133 are 115 advanced by means of the cam disk 168, so that the roller 154 is moved toward the roller 155 and the brush 151 folds the end of the label hanging down along the one side of 120 the article, over and brushes it against the bottom of the article. Then the plate 148 of the advancing slide 131 bears against the article and pushes it sidewise over the rollers 158 onto the conveyer belt 167. Thereby 125 the front ledge 162 presses the end of the 130

label hanging down between the rollers 155 and 158 on the one side of the article, against the bottom of the latter and the rollers 158 smooth down this end, so that the article reaching the conveyer belt is completely labeled.

The several operations at the various stages are simultaneous, so that a very rapid work is obtained. When the machine is to 10 run idle, the pile of labels is lifted by reversing the lever 18, and the cams 12 will lift the guides of slide 9.

It is obvious that various changes may be made with respect to the construction of the 15 above described machine without departing from the spirit of my invention.

I claim:

1. A labeling machine, consisting of a reciprocating pile of labels, a revolving segment roller, which draws by means of gum 20 the label from the pile, a second revolving segment roller, having one segment and several rotatable rollers and adapted to draw the label from the first roller, so that 25 it lies with the gummed side outside on the second segment roller and the rollers, means for intermittently advancing the articles to be labeled past this second segment roller, whereby the labels are pasted to the said 30 articles and smoothed down by the said rollers.

2. A labeling machine consisting of a reciprocating slide, a label container on said slide, tongues, fitted to levers and engaging 35 beneath said label container, means for rocking the levers with the tongues, a rack on the label container, revoluble rollers, on which the pile of labels rests, gears, attached to said rollers and engaging in said rack, and 40 means for drawing the label from the pile and applying it to the article to be labeled.

3. A labeling machine consisting of a reciprocating label container, rockably fitted 45 tongues, rising and falling cam rails adapted to remove said tongues from the pile of labels, supporting rollers for the pile of labels, said rollers adapted to revolve forward and backward at the reciprocation of the label container, and means for drawing 50 the label from the pile and for applying it to the article to be labeled.

4. A labeling machine consisting of a re-

ciprocating label container, means for supporting the labels in said container, means for drawing the label from the pile by aid 55 of gum, means for applying the label to the articles to be labeled, a table, onto which the said articles are placed, rising and falling slide guides, in said guides a reciprocating slide, dogs on said slide, said dogs, when in 60 raised position of the slide, projecting through slots in said table in an upward direction.

5. A labeling machine consisting of a reciprocating label container, tongues adapted 65 to be rocked aside, for supporting the pile of labels, rising and falling cam rails for operating said tongues, a rack on said label container, rollers, on which the said label container rides during its reciprocation, gears 70 attached to said rollers, a revoluble segment roller adapted to draw the label from the pile, means for applying gum to said roller on its segment, a second revolving roller, having one segment and behind the same 75 several revoluble rollers, and adapted to draw the label from the first segment roller, grippers at the second roller, adapted to seize the front edge of the label in drawing it from the first roller, a table with longitudinal slots onto which the articles to be labeled are placed, rising and falling guides, in said guides a reciprocating slide, dogs on 80 said slide, said dogs projecting at a raised position of said slide through the slots in 85 said table, brushes adapted to be moved up and down and to fold wide labels over and against the sides of the articles to be labeled and to smooth them down there, a heavy stamp, adapted to be lowered onto the said 90 articles and hold them tight, a displaceable roller and several stationary rollers onto which the said articles pass, a brush adapted to fold over wide labels also against the bottom of said articles, means for simultaneously operating the brush and the displaceable roller, a slide adapted to push the said articles from the stationary rollers, said stationary rollers adapted to thereby fold over the label against the bottom of the 95 100 article.

In testimony whereof I have hereunto set my hand.

EMIL JAGENBERG. [L.S.]
